CHAIN GRATE STOKER

Alfred Edward Parker, London, England, assignor
to The Babcock & Wilcox Company, Bayonne,
N. J., a corporation of New Jersey

Application October 12, 1929, Serial No. 399,143
In Great Britain December 6, 1928

5 Claims. (Cl. 110—40)

This invention relates to a chain grate stoker in which grate bars that may be broken or burned away do not interfere with the operation. Cross bars are provided to support the ends of the grate bars. These cross bars are firmly connected to other cross members and provide a box-like girder construction for the support of the grate bars. Special grate bars are provided along the sides of the grate so that ashes may collect to provide 10 a seal between the edges of the stoker and the stationary side walls.

The invention will be understood from the description in connection with the accompanying drawings in which Fig. 1 is a perspective view of part of the upper run of the stoker partly broken away and with some of the grate bars omitted; Fig. 2 is a vertical cross section partly broken away through a side portion of the stoker; Fig. 3 is a side view of one of the special grate bars; 20 Fig. 4 is a sectional view partly broken away taken longitudinally of the stoker, showing some of the details; and Fig. 5 is a similar view on an enlarged scale.

In the drawings, reference character 1 indicates a series of grooved wheels that are mounted on shafts 2 that are journaled in inner and outer link members 3, so that the wheels travel along the guide rails 4.

Plates 6 extending transversely of the stoker 30 are provided, upon which the grate bars for supporting the fuel are pivotally mounted, said plates having bulbous heads 5 formed on their upper edges. Each grate bar 7 has as bottom recess 8 near one end shaped to fit the bulb portion of one 35 of the plates 6 and the lower edges of the recess 8 of alternate grate bars in each transverse row are cut away, as indicated at 9, to permit a greater amount of pivoting or turning of these grate bars 7 on the plates 6 than of the intermediate grate 40 bars, thus providing a scissors-like action between adjacent grate bars to clear the accumulation of ash therebetween. Referring to Figs. 4 and 5 of the drawings it will be understood that this scissors-like action takes place when the grate 45 bar behind (and aligned with, transversely of the grate) the right hand bar 7 is not cut away as shown at 9, this relationship of adjacent bars being continued all the way along the corresponding plate 6. The grate bars 7 may be provided 50 with sloping end portions in the usual way.

Transverse bar supports 10 have their ends connected by bolts 11 to flanges of channel irons 12 which are riveted or otherwise connected, as indicated at 13, to the inner links 3. Bolts 14 connect the plates 6 to other flanges of the chan-

nel irons 12. Channel irons 15 are connected to the outer sides of the outer links 3 and the plates 6 are secured by means of the bolts 16 to the channel irons 15.

Grate bars 17 of special design, which differ from the grate bars 7, are connected to the ends of the plates 6. The grate bars 17 are provided with recesses 18 in their outer surfaces to receive cotter pins 19 which pass through the plates 6 and lie in the recesses 18 to keep the grate bars 10 17 on the plates 6.

A stationary side wall 20 is provided along each side of the chain grate stoker and an angle iron 21 is connected to the inside of each wall 20 near the lower ends of the grate bars 17.

By the grate bar rests 10, provision is made for supporting grate bars which may have had the sloping ends thereof broken off or burned away too much to rest upon the succeeding grate bars, and the grate bar rests 10 being connected to the framework form girders for supporting the grate bars and strengthening the stoker. The provision of the special grate 17 at the edges of the stoker makes it possible for the ashes to form seals along the edges of the stoker as the ashes 25 collect in the spaces between the sides of the grate bars 17 and the wall 20 and between the lower ends of the grate bars 17 and the upper flanges of the angles 21.

I claim:—

1. In a chain grate stoker-fired furnace, an endless grate frame comprising a series of pivotally connected links at opposite sides of said frame, rigid transversely extending plates connected to pairs of corresponding links at the opposite sides of said frame and projecting beyond the outer sides of said links, a series of transversely extending rows of fuel supporting grate bars carried by said plates, and grate sealing members each having a flat outer side mounted on and substantially flush with the projecting portion of each of said plates, a recess in said flat outer side, and means in said recess for detachably connecting each grate sealing member and the corresponding plate, said sealing members coacting with an adjacent furnace wall structure to provide an ash receiving pocket along the side of said stoker, the grate sealing members capping the rigid plates to hold their grate bars in their operative positions.

2. In a chain grate stoker-fired furnace, a track, an endless grate frame adapted to travel around said track and comprising a series of pivotally connected links at opposite sides of said frame, rigid transversely extending plates con-

- 5 nected to pairs of corresponding links at the
opposite sides of said frame and projecting be-
yond the outer sides of said links, track engaging
wheels carried by said links, a series of trans-
5 versely extending rows of fuel supporting grate
bars carried by said plates, grate sealing members
each having a flat outer surface slotted to receive
the projecting portion of one of said plates and
having a recess formed therein intersecting said
10 slotted portion, and means positioned in said
recess for connecting said sealing member to said
plate, the grate sealing members capping the
rigid plates to hold their grate bars in their
operative positions.
- 15 3. In a chain grate stoker, a track, an endless
grate frame adapted to travel around said track
and comprising a series of pivotally connected
links at opposite sides of said frame, a rigid
transversely extending supporting bar connecting
20 corresponding links at opposite sides of said
frame adjacent one end thereof, rigid trans-
versely extending plates connected to said corre-
sponding links at opposite sides of said frame at
points spaced forwardly of corresponding sup-
25 porting bars and each having a bulbous head pro-
jecting above the upper edges of said links and
supporting bar in the upper run of said stoker,
track engaging wheels carried by said links, and
a series of transversely extending rows of grate
30 bars, each having a recess in its under side re-
ceiving the bulbous head of a corresponding plate
and having its rear end arranged to rest on the
forward portion of a corresponding grate bar in
the succeeding row while in the upper run of the
35 stoker and on the associated supporting bar
whenever it is unable to engage said correspond-
ing grate bar in said upper run.
4. In a chain grate stoker, a track, an endless
grate frame adapted to travel around said track
40 and comprising a series of pivotally connected
links at opposite sides of said frame, a rigid
transversely extending supporting bar connecting
corresponding links at opposite sides of said frame
adjacent one end thereof, rigid transversely ex-
45 tending plates connected to said corresponding
links at opposite sides of said frame at points
spaced forwardly of the corresponding supporting
bars and each having a bulbous head projecting
above the upper edges of said links and support-
50 ing bar in the upper run of said stoker, track
engaging wheels carried by said links, a series of
transversely extending rows of grate bars, each
having a recess in its under side pivotally re-
ceiving the bulbous head of a corresponding plate
55 and having its rear end arranged to rest on the
forward portion of a corresponding grate bar in
the succeeding row while in the upper run of the
stoker and on the associated supporting bar
whenever it is unable to engage said correspond-
60 ing grate bar in said upper run, the alternate grate
bars in each row having a larger recess to permit
pivotal movement relative to the plates associated
therewith greater than adjacent grate bars in the
same row.
- 65 5. In a chain grate stoker, a track, an endless
grate frame adapted to travel around said track
and comprising a series of pivotally connected
links at opposite sides of said frame, a rigid
transversely extending supporting bar connecting
70 corresponding links at opposite sides of said frame
adjacent one end thereof, rigid transversely ex-
tending plates connected to said corresponding
links at opposite sides of said frame at points
spaced forwardly of the corresponding support-
75 ing bars and each having a bulbous head project-
ing above the upper edges of said links and sup-
porting bar in the upper run of said stoker, said
plates projecting beyond the outer sides of said
links, track engaging wheels carried by said links,
80 a series of transversely extending rows of grate
bars, each having a recess in its under side pivot-
ally receiving the bulbous head of a corresponding
plate and having its rear end arranged to rest on
the forward portion of a corresponding grate bar
85 in the succeeding row while in the upper run of
the stoker and on the associated supporting bar
whenever it is unable to engage said correspond-
ing grate bar in said upper run, and grate sealing
members mounted on the projecting portions of
90 said plates and adapted to coact with an adja-
cent wall to form a seal for said stoker.

ALFRED EDWARD PARKER.
